(57) **CLAIM**

What is claimed is the ornamental design for a modular wall assembly, as shown and described.

DESCRIPTION

FIG. 1 is a perspective view of a modular wall assembly. FIG. 2 is a front elevation view of the modular wall assembly of FIG. 1.

FIG. 3 is a rear elevation view of the modular wall assembly of FIG. 1.

FIG. 4 is a left elevation view of the modular wall assembly of FIG. 1.

FIG. 5 is a right elevation view of the modular wall assembly of FIG. 1.

FIG. 6 is a top plan view of the modular wall assembly of FIG. 1; and,

FIG. 7 is a bottom plan view of the modular wall assembly of FIG. 1.

The evenly-spaced broken lines and the dash-dot broken lines in the figures represent environmental structure that forms no part of the claimed design.

1 Claim, 5 Drawing Sheets
